FEELER MECHANISM FOR LOOMS

Application filed April 10, 1931. Serial No. 529,065.

This invention relates to feeler mechanisms for looms and is more particularly directed to feeler mechanisms of the electric type wherein upon substantial exhaustion of filling a change is made in the loom operation.

Feeler mechanisms of the electric type now ordinarily comprise two feeler members which are mounted upon a feeler stand to contact with the filling on detecting beats and upon substantial exhaustion of filling to be electrically connected by means of a metal piece or sleeve on the filling carrier or bobbin. The feeler members of such electrical feeler mechanisms are usually formed of a rod which is urged rearwardly by a spring to enter the shuttle and detect the condition of the filling. Since the feeler members as now ordinarily employed move in a straight path towards and from the front of the loom on detecting beats and the lay moves in a curved path much injury is sometimes produced on the filling. It will happen at times also that the feeler members may engage the filling while the shuttle is still in motion and here again the filling is injured.

It has been proposed heretofore to produce an electric feeler member of the rod type with a yieldingly mounted or flexible filling engaging tip in an attempt to obviate filling injury.

One of the objects of the present invention is to provide a feeler mechanism for looms wherein the filling feeler, preferably of the electric type, is so formed and constructed that it is of light character, is flexible throughout and cheap and readily manufactured.

More specifically stated, the filling feeler of the present invention as shown is formed of a continuous wire wound into a helical spring, one portion of which is of less pitch between the coils of the wire than another portion, so that the filling feeler is self contained.

In accordance with the present invention the helical spring which constitutes the filling feeler is of two diameters; the larger diameter which constitutes the supporting

element for the feeler is an open helix, while the portion of smaller diameter is a closed helix and extends rearwardly to engage a surface within the shuttle on detecting beats.

While the invention is shown and described as especially advantageous in the electrical type of feeler mechanisms, certain aspects of the invention are not necessarily limited thereto, but for the present purposes the invention will be described in connection with an electric feeler mechanism.

The invention and novel features thereof will best be made clear from the following description and accompanying drawings of one good form thereof.

In the drawings:—

Fig. 1 is a plan view showing the present invention with some portions of the shuttle broken away;

Fig. 2 is a section on the line 2—2 of Fig. 1;

Fig. 3 is a view similar to that of Fig. 2 showing the feeler of the present invention without the separate tip portion of Fig. 2.

The loom frame 1 may be of usual construction and provided with a supporting bracket 2 of any desired character and mounted upon the bracket 2 is the feeler stand 3 formed of insulating material, and secured to the bracket 2 by means of a bolt 4.

The feeler stand 3 supports the two filling feelers, each of which is constituted by wire wound into a helical spring, and since both filling feelers may be of the same construction a description of one will be sufficient.

The filling feeler, as indicated in the drawings, has an open helical portion 5 and a substantially closed helical portion 6, that is the feeler, as shown, is formed of a continuous wire wound into a helical spring, the forward portion of which, as at 5, has the coils of the helix on a different pitch from the coils of the helix at the lesser diameter, as at 6, and the open helix portion 5 is contained within a recess formed in the feeler stand, as shown more clearly in Fig. 2 so that the forward end of the open helix may rest upon an abutment or adjusting screw 7 whereby the open helix portion of larger diameter may exert a tendency to move the feeler as a whole into its rearward feeling position.

At the point where the larger diameter of the helix connects with the portion of smaller diameter there is a shoulder formed by the convolutions of the helix where the two portions unite. In the present instance the shoulder portion is formed in conical shape, as indicated at 8, Fig. 2, and cooperating with the shoulder 8 the insulating casing is provided with a stop 9, against which the shoulder contacts when the open helix at 5 has moved the feeler to its rearward feeling position.

The rear portion of the filling feeler, as hereinbefore noted, is what may be termed a closed helix, that is the convolutions of the wire forming the helix are wound close together, so that while the rear portion 6 of the filling feeler may yield in any direction by virtue of its spring wire construction, the closely laid convolutions will transmit the forward push of the surface within the shuttle on a detecting beat to the larger open portion of the helix at 5, whereby the filling feeler may be moved forwardly by the forward pressure and when such pressure has been released the open helix 5 will move the feeler as a whole to its rearward feeling position until the shoulder 8 engages the stop 9 at the rear of the feeler stand, thereby positioning the feeling end of the helix to enter the shuttle on detecting beats and feel for the filling.

The open helix portion 5 of each filling feeler is continuous in circuit with an electric conductor. One of the conductors 10 is electrically connected to a plate 11 conveniently held in place at one end by the securing bolt 4 while its front end portion is down turned, as at 12, and is in electrical connection with the adjusting screw or other abutment 13, against which the open helix 5 rests at all times, with the result that the coils of the open portion of the helix are in continuous contact with an electric conductor, and to maintain such contact undisturbed the bolt 40 or plug 13 has threaded to it a nut 14 between which and the stand 3 the down turned end 12 of the plate 11 is secured.

Connected with the open helix of the companion filling feeler is a conductor 15 which enters a metallic bushing 16, an end portion of which may bear directly upon the coils of the open helix. The construction described for maintaining continuous engagement of the two open helices with electric conductors may be variously contrived, but the construction described is a convenient form of this feature.

Each of the filling feelers is supported to enter the shuttle on detecting beats and feel for the filling, as indicated in Fig. 1, and as will be noted the shuttle 17 has an opening 18 in its front wall and the filling carrier 19 is provided with a circuit closing member 20, shown in the present instance of the invention as a metallic sleeve, the result being that

when filling has become substantially exhausted the rear end portions of the helical spring filling feelers will engage the circuit closing member 20 and complete the circuit thereby effecting a change in the loom operation.

It may be desirable at times to provide each of the helical spring filling feelers with a separate tip portion rather than have the end of the helix 6 engage the filling, as indicated in Fig. 3, but this is not always necessary, although when used as indicated in Fig. 2 the contacting tip 21 may be threaded into the interior coils of the closed helix 6 as at 22 thereby establishing electrical connection between the separate tip when used and the coils of the helix.

From the construction described as one embodiment of the present invention it will be noted that each filling feeler is formed of a continuous wire wound into a helix of two diameters, one of which constitutes the open helix 5 for moving the feeler into rearward feeling position, and the other of which 6 of lesser diameter takes the thrust of the oncoming filling by virtue of its closely wound condition. And while the thrust may be taken by the so-called closed helix 6, the latter may yield in any direction to accommodate itself to any inaccuracy of the shuttle position or even during shuttle movement.

The filling feeler of the present invention which is constructed throughout from a continuous wire wound into a helical spring provides a light and easily manipulated filling feeler which accommodates itself automatically to any conditions which require flexibility of the feeler and avoids the supplemental use of rigid members, such as a rod, pin or the like for guiding the feeler in its forward or rearward movements. The filling feeler is self-contained and while it is especially adapted for use in the electrical type of feeler mechanisms features thereof are not necessarily confined to this use and while the forward end of the open helical portion 5 of the filling feeler may rest conveniently against an adjusting pin or bolt, such as 7, it is clearly obvious that some other form of a rest or abutment may be employed.

What is claimed is:

1. In a feeler mechanism for looms, an electric filling feeler constituted as a single helical spring one portion of which is a more open helix than the other.
2. In a feeler mechanism for looms, an electric filling feeler constituted as a single helical spring of two diameters, the larger diameter being formed as an open helix.
3. In a feeler mechanism for looms, an electric filling feeler constituted as a single helical spring of two diameters, the larger diameter being formed as an open helix and a shoulder formed by the convolutions of the

helix where the larger and smaller diameters of the helix connect.

4. In a feeler mechanism for looms, an electric filling feeler formed as a single helical spring of two diameters and a conical shoulder at the union of the larger and smaller diameters of the helix.

5. In a feeler mechanism for looms, the combination of the feeler stand formed of insulating material, an electric feeler constituted as a single helical spring of two diameters, the larger diameter being mounted in the insulating feeler stand, a shoulder formed by the convolutions of the helix where the larger and smaller diameters of the helix connect, and a stop on the feeler stand for engagement by said shoulder when the feeler is in rearward position.

6. In a feeler mechanism for looms, a feeler stand formed of insulating material, two electric filling feelers supported by the feeler stand and each constituted as a single wire wound into a continuous helical spring having one portion formed as an open helix mounted on the feeler stand to yieldingly urge the feeler as a whole to its rearward feeling position, a shoulder formed at the rear portion of the open helix of each feeler, and a stop for engagement by the shoulder to limit rearward movement of the feeler.

7. In a feeler mechanism for looms, a feeler stand formed of insulating material, two electric feelers supported by the feeler stand and each constituted as a continuous wire wound into a helical spring having one portion formed as an open helix mounted on the feeler stand and the other portion as a more closed helix extending rearwardly, and an electric conductor is continuous electric connection with each open helix.

8. In a feeler mechanism for looms, a filling feeler formed complete of a continuous wire wound into a helical spring that the feeler may yield in any direction on contact with a surface within the shuttle.

9. In a feeler mechanism for looms, an electric feeler formed complete of a continuous wire wound into a helical spring, the front portion of the spring being formed as an open helix and the rear portion being formed as a closed helix.

10. A filling feeler for looms made of wire wound into helical form and comprising two connected helical portions of different diameters.

11. A filling feeler for looms made of wire wound into helical form and comprising two helical portions of different diameters connected together end to end, one of the helical portions being a more open helix than the other.

12. A filling feeler for looms formed of wire wound into helical form and comprising two helical portions of different diameters connected together, the portion of larger di-

ameter being an open helix and the portion of smaller diameter being a closed helix.

In testimony whereof, I have signed my name to this specification.
